UNITED STATES PATENT OFFICE.

WILLIAM BUTTLER, OF REDKEY, INDIANA.

DESIGN FOR SHEET-GLASS.

SPECIFICATION forming part of Design No. 35,161, dated October 1, 1901.

Application filed August 16, 1901. Serial No. 72,310. Term of patent 14 years.

To all whom it may concern:

Be it known that I, WILLIAM BUTTLER, of Redkey, in the county of Jay and State of Indiana, have invented a new and original Design for Sheet-Glass, of which the following is a full, clear, and exact description, reference being had to the accompanying drawings, forming part of this specification, in which—

10 Figure 1 is a rear view showing sheet-glass constructed in accordance with my invention. Fig. 2 is a front elevation, and Fig. 3 is a cross-section.

In the drawings the sheet of glass is shown 15 as provided upon its front face with a series

of ribs or corrugations 2. The rear face of the glass is provided with a series of figures composed of rays 3, emanating from points 4 and surrounded by a border composed of a band 5 of irregular contour.

I claim—

The design for a sheet of glass substantially as herein shown and described.

In testimony whereof I have hereunto set my hand.

WILLIAM BUTTLER.
